ELECTRON DISCHARGE DEVICE FOR ULTRA HIGH FREQUENCIES

Philip T. Smith and Howard R. Hegbar, Princeton, N. J., assignors to Radio Corporation of America, a corporation of Delaware

Application March 18, 1943, Serial No. 479,550

17 Claims. (Cl. 315—6)

1

Our invention relates to electron discharge devices and associated circuits useful at ultra high frequencies, more particularly to such devices utilizing closed resonant circuits or resonators.

At the higher frequencies, the physical dimensions of tuned circuits are small. Thus when tubes are to be used in conjunction with these circuits the tube elements become an appreciable physical part of the circuit. In present ultra high frequency technique of closed resonant circuits or resonators, which provide particularly suitable circuits at ultra high frequencies, are directly coupled to the electrodes of an electron discharge device. In one form of device such as the so-called "grounded grid" triode, use is made of two closed resonant circuits or resonators. One of these resonators is coupled between the cathode and the grid and the other is coupled between the grid and the collector or anode, radio frequency energy being extracted from the closed resonant circuit between the grid and anode by means of a coupling loop. In one form of such tube the grid structure almost completely electrically isolates the interior of one resonator from the other.

For microwaves at ultra high frequencies, the time required for an electron to traverse any practical cathode-grid distance becomes an appreciable fraction of the wave period resulting in undesirable losses both in the input and output circuits. As a consequence for the efficient operation of these tubes and particularly as an oscillator it becomes necessary to compensate for this transit time. A partial compensation for transit time losses may be obtained if the radio frequency voltage of the grid-cathode resonator operates at a leading angle with respect to the radio frequency voltage of the grid-collector resonator. This can be done by feeding back energy from the plate resonator to the cathode resonator in the proper phase by employing complicated external transmission lines.

It is an object of our invention to obtain an electron discharge device and circuit particularly useful at ultra high frequencies.

A further object of our invention is to provide such an electron discharge device and circuit which will compensate for electron transit time effects.

More specifically it is an object of our invention to provide a leading angle between the radio frequency voltage in the grid-cathode resonator and the radio frequency voltage in the grid-plate resonator of apparatus utilizing an electron discharge device and resonators.

2

A still further object of our invention is to provide such a leading angle in such a device without using external transmission lines.

The novel features which we believe to be characteristic of our invention are set forth with particularity in the appended claims, but the invention itself will best be understood by reference to the following description taken in connection with the accompanying drawing in which Figure 1 is a longitudinal section of one form of an electron discharge device and circuit made according to our invention, Figure 2 is a transverse section taken along the line 2—2 of Figure 1 showing details of the grid construction, Figure 3 is a modification of the structure shown in Figure 2, Figure 4 is an equivalent circuit diagram of the device shown in Figure 1, Figure 5 is a longitudinal section of a modification of an electron discharge device made according to our invention, and Figure 6 is a schematic longitudinal section of the tube structure and associated circuits.

An electron discharge device and associated circuit made according to our invention is shown in Figure 1. The cathode includes a cup-shaped element 10 heated by heater 11 and coated, in a manner to be described, with emitting material 12.

A grid 14 of a construction to be described and having the same cross sectional configuration is positioned between the indirectly heated cathode 10 and the collector or anode 13, provided with a concave surface so that the surfaces of the cathode, grid and anode nest within each other.

The cathode-grid resonator which may be used as an input resonator and coupled between the cathode and the grid comprises the inner cup-shaped member 15 and the outer cup-shaped member 18 having a bottom element 17 which closes one end of the tube and provides a support for the member 15, which is secured by screws 18

extending through the flange on member 15 into the element 17. The member 15 supports at its inner end the circular block 19" on which the cathode 10 is secured by the collar 19 and screws 19", a mica ring 20 electrically insulating the cathode from the inner tubular member 15. The cathode is provided with a hollow tubular cathode lead 21 provided with the tubular flange 23 and sealed to the element 17 by means of the glass tubular member 22.

This cathode lead 21 also acts as the outer conductor of a cooling system provided with an inner tubular member 24, the cooling medium passing into the interior of the cathode through one of the tubular members and outwardly through the other tubular member in a manner well known. The tubular member and

lead 21 may also serve as one of the heater leads for the heater 11. The other lead 25 is sealed through the element 17 by means of the collar 26 and seal 27, the lead being insulatingly protected by tubular insulating elements 28.

The anode-grid resonator which may be the output resonator and coupled between the anode and the grid includes the outer tubular member 30 coaxial with and surrounding the inner tubular member 31, their ends being closed by transverse element 32 integral with the outer tubular member 30, the two members being secured together by means of screw elements 33. The anode or collector 13 is insulatingly supported on the inner element 31 by means of the insulating discs or mica collars 34, a screw member 37 securing the collector to the inner tubular member 31 by means of the clamping disc 35 and insulating collar member 36. Thus while the collector is a part of the resonator circuit it is insulated from it to permit a different D. C. potential to be applied to the collector through either of the two leads 38 or 40 provided with the sealing member 39 sealed to the element 32 by means of the tubular insulating member 32'. The members 38 and 40 may be used to introduce a cooling medium to the interior of the collector 13.

The grid 14, closing the ends of the resonators connected between the cathode and the grid and between the grid and the anode, is supported by the flange element 16' to which it is secured by screws, the two portions of the device being clamped together by means of the screw member 45 extending through the flange 16' and into the flange 30' on the outer tubular member 30 of the grid-anode resonator. A gasket 46 may be provided between the two flanges. If desired continuous pumping can be used to maintain a vacuum within the device by connecting tube 41 to a pump, but the structure may be sealed off from the pump. A coupling loop 44 to permit coupling of the energy from the anode-grid resonator coupled between the grid and the collector is positioned within the reentrant seal 43.

In order to assure desirable and most efficient operation of the device shown in Figure 1, the electrons received by the collector or anode should reach the anode at such time that the radio frequency voltage on the anode is a minimum. In this way maximum energy is delivered to the anode circuit with the least dissipation of energy in the form of heat, which reduces the efficiency of the apparatus. At the lower frequencies the voltage on the grid is 180° out of phase with the voltage on the anode, and electrons from the cathode move between the cathode and the collector in the period of time which is extremely short in comparison with the period of the applied voltage to the grid, so that the electrons reach the anode at the proper time, or when the anode radio frequency voltage is a minimum. At the higher frequencies however, the transmit time of the electrons between the cathode and anode or collector forms an appreciable part of the period of the applied voltage so that the electrons reach the anode or collector at a time when the voltage is not a minimum or not 180° out of phase with the grid voltage. Thus the electrons are collected by the anode at a time when the voltage on the anode is greater than the desirable voltage causing more of the energy to be lost in the form of heat. It would, therefore, be desirable to have the electrons leave the cathode at such time that they will reach the anode when the *r-f* potential is a minimum.

Stated another way, at the lower frequencies it is desirable to have the cathode *r-f* voltage swing in phase with the anode *r-f* voltage, since the electrons from the cathode move between the cathode and collector in a period of time which is small in comparison with the period of the applied *r-f* voltage. At the higher frequencies, however, the transit time of the electrons between the cathode and anode or collector forms an appreciable part of the period of the applied *r-f* voltage so that under the above conditions the electrons reach the anode or collector after the voltage has reached a minimum, so that the electrons are collected by the anode at a time when the voltage on the anode is greater than the desirable voltage causing more energy to be lost in the form of heat. We partially compensate for this effect by providing a leading angle between the cathode-grid *r-f* voltage with respect to the anode-grid *r-f* voltage. A leading angle is attained if a resistive component is added to the capacitive reactance of the cathode-grid resonator. The energy losses in the cathode-grid resonator, due to loading by conduction currents and heating from circulating currents provide this resistive component. This angle can be further changed or partially controlled by taking out at least part of the output energy from the cathode-grid resonator.

In other words, the input resonator must display a capacitive reactance. In a device utilizing a coaxial line resonant cavity or resonator, the length of the line should be so chosen that it is substantially a one-quarter or a three-quarter or any odd multiple of a quarter wavelength long. This will cause the input circuit or the grid-cathode circuit to display a capacitive reactance. Thus the electrons can be made to reach the anode when the *r-f* voltage is at a minimum.

In order to provide the necessary feedback between the two resonators so that the device may function as an oscillator without the use of an external transmission line, we provide a grid of novel construction. As shown in Figure 2 the grid 14' is provided with a large central aperture 50 and with a plurality of smaller apertures surrounding this aperture 50. At the periphery of the grid we provide a plurality of apertures of larger size than the apertures 52 for a purpose to be described. In the form shown in Figure 3 the grid 14' is provided with transverse wires 52' extending across the grid and with the outer apertures 51'.

The purpose of the central aperture 50 is to increase the capacity coupling between cathode and anode to such an extent that the desired feedback will occur within the tube. The purpose of the smaller apertures 52 is to obtain the necessary control of the electrons passing between the cathode and grid so that the grid will retain its normal control. The apertures 51 provide an electromagnetic coupling between the fields within the two resonators. In order to prevent emission between the grid and cathode at the point where only capacity coupling is desired, that is through the aperture 50, the portion of the cathode surface registering with this aperture is not coated and to reduce the grid current which might otherwise occur, the cathode is coated only on those portions of its surface registering with the apertures 52.

In the form of grid shown in Figure 3 the cathode surface is coated only on those portions of the cathode surface registering with the space between the grid wires 52'.

An equivalent circuit diagram of our device is shown in Figure 4. The elements K, G and P represent the cathode, grid and plate. The elements L_1 and C_1 connected between grid and cathode represent the distributed capacity and inductance of the input resonator comprising elements 15, 16 and 17, while the resistance R_1 represents the resistance of the resonator circuit and the resistance due to the grid loading between the grid and the cathode.

The capacity C_2 and inductance L_2 represent the distributed inductance and capacity of the output resonator comprising elements 30, 32 and 34 and the resistance R_2 is that of the circuit and the resistance between plate and grid when current flows. The capacity C_{58} represents that capacity existing between the cathode and anode due to the aperture 59 at the center of the grid, the symbol 14 representing the electromagnetic coupling through the openings 51 existing between the two fields within the resonators. According to our theory aperture 59 provides the return circuit for the radio frequency currents. Thus the electrons leaving the cathode at a leading angle with respect to the $r-f$ voltage within the resonator pass through the grid into the resonator coupled between the anode and the grid and arrive at the anode at the proper time.

Part of the energy from the anode-grid resonator is fed back into the cathode-grid resonator by means of the capacity between the anode and cathode, through the apertures 58 and 52. The aperture 58 makes it possible to adjust this capacity. The circuit is completed through the aperture 51. In other words, the capacity through the apertures 58 and 52 is represented by C_{58} in Figure 4 whereas the apertures 51 complete the circuit at 14 in Figure 4.

Figure 6 is a schematic longitudinal section of an electron discharge device made according to our invention and the connections between the various elements and the source of voltages necessary for the operation of the device. A cathode heating voltage is applied by means of the heating transformer 55 and bias on the grid with respect to cathode obtained by biasing resistor 56 through which the cathode is connected to ground, grid 14 being connected to ground at 58. Collector voltage is shown at 59.

While we have shown in Figure 1 an arrangement in which the electrodes extend transversely of the coaxial line resonators, in Figure 5 we show a modification in which the cathode and grid and anode merge into the longitudinal surface of the concentric lines. As shown in Figure 5 the cathode 60 is provided with a heater 61, the cathode 60 serving as an extension of the internal coaxial member 66. The cathode 60 is supported on member 66 by means of the insulated screw members 66'' clamping the cathode to the inner tubular member 66 but insulated therefrom by means of the insulator or mica separator 66'. Surrounding the cathode is a grid 63 provided with longitudinally extending wires forming an extension of the outer tubular member 68 and having cap 62 provided with aperture 64. The members 66 and 68 provide an input resonator connected between the cathode and grid, the cathode again being coated only on the portions registering with the apertures between the grid wires and not being coated at its end in registry with the apertures 64 and cap 62. The output resonator connected between the grid and collector is formed by means of the cup-shaped member 65 serving as the collector and the outer

tubular member 69 insulatingly connected to member 65 by means of the separator 69' which may be of mica and screws 69'', the coaxial member 68 and 69 providing the outer resonator. The cathode heater leads 67 extend through tubular sealing member 67' sealed to the inner tubular member 66 and collector lead-in 72 extends through tubular member 73 which is sealed to the outer casing 70 which may be evacuated and sealed off at 74. A reentrant seal 71 may be provided to permit the insertion of a coupling loop 75 within the output resonator to extract energy from the field within this resonator.

As in the other forms, the capacity coupling is provided through aperture 64 and the fields within the resonators are coupled by means of the apertures 68' formed in the outer tubular member 68 of the cathode-grid resonator. The device otherwise functions in a manner similar to that shown in Figure 1.

A device of the kind described operated satisfactorily at about 600 megacycles with reasonable efficiency. Tests also indicated that the tube functioned in the manner described above.

While we have indicated the preferred embodiments of our invention of which we are now aware and have also indicated only one specific application for which our invention may be employed, it will be apparent that our invention is by no means limited to the exact forms illustrated or the use indicated, but that many variations may be made in the particular structure used and the purpose for which it is employed without departing from the scope of our invention as set forth in the appended claims.

What we claim as new is:

1. An electron discharge device having a cathode and an oppositely disposed anode, a conducting partition positioned between said cathode and said anode and including a grid, a resonator coupled between said partition and cathode, and a second resonator coupled between said partition and anode, said cathode having emitting and substantially non-emitting areas, the grid portion of said partition being provided with apertures registering with said emitting areas and said partition having another aperture providing a passageway between said resonators for providing electromagnetic coupling, said grid having another aperture to provide anode-cathode capacity feedback coupling, said last aperture registering with a non-emitting portion of said cathode.

2. An electron discharge device having a cathode and an oppositely disposed anode, a resonator coupled to said cathode, and a second resonator coupled to said anode, said resonators having a common conducting partition between them, said partition providing a grid positioned between said cathode and said anode, said cathode having emitting and substantially non-emitting areas, said partition being provided with an apertured portion registering with an emitting area on said cathode surface, and said partition having an apertured portion providing a passageway between the interior of said resonators for providing electromagnetic coupling, said grid having another aperture to provide anode-cathode capacity feedback coupling, said last aperture registering with a non-emitting portion of said cathode.

3. An electron discharge device having a cathode and an oppositely disposed anode, a conducting partition positioned between said cathode and said anode and including a grid portion, a

resonator coupled between said partition and cathode and enclosing said cathode, and a second resonator coupled between said grid and anode and enclosing said anode, said cathode having emitting and substantially non-emitting areas, the grid portion of said partition being provided with apertures registering with said emitting areas, and said partition having other apertures providing passageways between the interior of said resonators for providing electromagnetic coupling, said grid having another aperture to provide anode-cathode capacity feedback coupling, said last aperture registering with a non-emitting portion of said cathode.

4. An electron discharge device having a cathode and an oppositely disposed anode, a grid positioned between said cathode and anode, a resonator coupled between said grid and cathode and enclosing said cathode, and a second resonator coupled between said grid and anode and enclosing said anode, said resonators being oppositely disposed, said grid providing a partition between said resonators, said cathode having a substantially flat surface with emitting and substantially non-emitting areas, said grid being provided with an aperture registering with an emitting area and at least one other aperture registering with a non-emitting area of said cathode.

5. An electron discharge device having a cathode and an oppositely disposed anode, a grid positioned between said cathode and anode, a resonator coupled between said grid and cathode and enclosing said cathode, and a second resonator coupled between said grid and anode and enclosing said anode, said resonators being oppositely disposed, said grid providing a partition between said resonators, said cathode having a substantially flat surface with emitting and substantially non-emitting areas, said grid being provided with apertures registering with emitting areas of said cathode, and a plurality of other apertures at least one of which registers with a non-emitting area of said cathode.

6. An electron discharge device having a cathode and an oppositely disposed anode, a grid positioned between said cathode and anode, a resonator coupled between said grid and cathode and enclosing said cathode, and a second resonator coupled between said grid and anode and enclosing said anode, said resonators being oppositely disposed, said grid providing a partition between said resonators, said cathode having emitting and substantially non-emitting areas, said grid comprising a plate-like structure provided with an enlarged aperture at its center and a plurality of smaller apertures, said cathode being provided on its surface with emitting areas registering only with the smaller apertures.

7. An electron discharge device having a cathode and an oppositely disposed anode, a grid positioned between said cathode and anode, a resonator coupled between said grid and cathode and enclosing said cathode, and a second resonator coupled between said grid and anode and enclosing said anode, said resonators being oppositely disposed, said grid providing a partition between said resonators, said cathode having a substantially flat surface with emitting and substantially non-emitting areas, said grid being provided with apertures registering with the emitting areas and having a plurality of apertures positioned near its periphery and providing passageways between the interiors of the resonators.

8. An electron discharge device having a cathode and an oppositely disposed anode, a grid positioned between said cathode and anode, a resonator coupled between said grid and cathode and enclosing said cathode, and a second resonator coupled between said grid and anode and enclosing said anode, said resonators being oppositely disposed, said grid providing a partition between said resonators, said cathode having emitting and substantially non-emitting areas, said grid comprising a plate-like structure provided with an enlarged aperture at its center and a plurality of smaller apertures surrounding said enlarged aperture, said cathode being provided with emitting areas only on its surface registering with the smaller apertures, said grid having a plurality of apertures positioned near its outer periphery, said last plurality of apertures providing passageways between the interiors of the resonators.

9. An electron discharge device having a cathode and an oppositely disposed anode, a grid positioned between said cathode and anode, a resonator coupled between said grid and cathode and enclosing said cathode, and a second resonator coupled between said grid and anode and enclosing said anode, said resonators being oppositely disposed, said grid providing a partition between said resonators, said grid having a centrally positioned enlarged aperture, a plurality of smaller apertures surrounding said enlarged aperture, a plurality of other apertures positioned near the outer periphery of said grid member, said cathode being coated with emitting material only on its surface registering with the plurality of smaller apertures.

10. An electron discharge device having a plate-like cathode, a plate-like anode, and a grid positioned between said cathode and anode, a concentric line resonator closed at one end and having an inner conductor and a tubular member surrounding said inner conductor, said cathode being insulatingly supported on said inner conductor remote from the closed end of said resonator, said grid extending across and closing the end of said resonator adjacent said cathode, a second concentric line resonator having one end closed and including an inner conductor surrounded by an outer tubular member, said anode being insulatingly supported on the inner conductor at the end of said second concentric line resonator remote from its closed end, the end of said second resonator adjacent said anode also being closed by said grid, said grid providing a partition between said resonators.

11. An electron discharge device having a plate-like cathode, an oppositely disposed plate-like anode, and a grid positioned between said cathode and anode, a concentric line resonator closed at one end and having an inner conductor and a tubular member surrounding said inner conductor, said cathode being insulatingly supported on said inner conductor remote from the closed end of said resonator, said grid extending across and closing the end of said resonator adjacent said cathode, a second concentric line resonator having one end closed and including an inner conductor surrounded by an outer tubular member, said anode being insulatingly supported on the inner conductor at the end of said second concentric line resonator remote from its closed end, the end of said second resonator adjacent said anode also being closed by said grid, said grid providing a partition between said resonators, said grid having a plurality of apertures

near its periphery providing passageways between the interiors of said coaxial line resonators.

12. An electron discharge device having a plate-like cathode, an oppositely disposed plate-like anode, and a grid positioned between said cathode and anode, a concentric line resonator closed at one end and having an inner conductor and a tubular member surrounding said inner conductor, said cathode being insulatingly supported on said inner conductor remote from the closed end of said resonator, said grid extending across and closing the end of said resonator adjacent said cathode, a second concentric line resonator having one end closed and including an inner conductor surrounded by an outer tubular member, said anode being insulatingly supported on the inner conductor at the end of said second concentric line resonator remote from its closed end, the end of said second resonator adjacent said anode also being closed by said grid, said grid providing a partition between said resonators, said grid being provided with an enlarged centrally positioned aperture and having a plurality of smaller apertures surrounding said centrally positioned aperture and a plurality of apertures near its periphery providing passageways between the interiors of said coaxial line resonators, said cathode having areas coated with emitting material and non-coated areas, said coated areas registering with the plurality of smaller apertures.

13. An electron discharge device having a cathode surrounded by a cup-shaped grid and a cup-shaped anode, a first tubular member supporting said cathode and a second tubular member surrounding said first tubular member and supporting said grid and providing with said first tubular member a first resonator coupled between the cathode and grid and a third tubular member surrounding said first and second tubular members, and supporting said cup-shaped anode and providing with said second tubular member a second resonator, said grid having an enlarged aperture in its cup-shaped end, the second tubular member supporting said grid having other apertures providing passageways between the interiors of said resonators.

14. An electron discharge device having a tubular indirectly heated cathode surrounded by a cup-shaped grid and a cup-shaped anode, a first tubular member insulatingly supporting said cathode and a second tubular member surrounding said first tubular member and supporting said grid and providing with said first tubular member a first resonator coupled between the cathode and grid and a third tubular member surrounding said first and second tubular members, and connected to but insulatingly supporting said cup-shaped anode and providing with said second tubular member a second resonator, said grid comprising a cap having an enlarged aperture in said cap and a plurality of longitudinally extending rod-like elements connected to said cap, said cathode being coated with emitting material only over its surface areas registering with the space between said rod like elements, said second tubular member having apertures providing passageways between the interior of said resonators.

15. An electron discharge device having a cathode, and an anode, and a grid positioned between said cathode and anode, a concentric

line resonator connected between said cathode and grid, said grid extending across and closing the end of said resonator adjacent said cathode, a second concentric line resonator connected between said anode and said grid, the end of said second resonator adjacent said anode being closed by said grid, said grid providing a partition between said resonators, said cathode having emitting and substantially non-emitting areas, said grid being provided with a plurality of apertures registering with the emitting areas of said cathode and having an apertured portion between the interiors of said concentric line resonators, the coaxial line resonator connected between said cathode and grid being a quarter wavelength long of the operating frequency of said electron discharge device.

16. An electron discharge device having a cathode and an anode, and a grid positioned between said cathode and anode, a concentric line resonator connected between said cathode and grid, said grid extending across and closing the end of said resonator adjacent said cathode, a second concentric line resonator connected between said anode and said grid, the end of said second resonator adjacent said anode being closed by said grid, said grid providing a partition between the interior of said resonators, said cathode having emitting and substantially non-emitting areas, said grid being provided with a plurality of apertures registering with the emitting areas of said cathode, and having an apertured portion between the interiors of said coaxial line resonators, the coaxial line resonators connected between said cathode and grid being of the order of an odd multiple of quarter wavelengths long of the operating frequency of said electron discharge device.

17. An electron discharge device having a cathode surrounded by a cup-shaped grid and a cup-shaped anode, a first tubular member connected to said cathode and a second tubular member surrounding said first tubular member and connected to said grid and providing with said first tubular member a first resonator coupled between the cathode and grid, and a third tubular member surrounding said first and second tubular members and connected to said cup-shaped anode and providing with said second tubular member a second resonator, the second tubular member connected to said grid having an aperture providing a passageway between the interiors of said resonators.
